UNITED STATES PATENT OFFICE.

LEWIS M. KELLOGG, OF SOUTH PASADENA, CALIFORNIA.

CASCADE-AMALGAMATOR.

1,386,875.

Specification of Letters Patent. Patented Aug. 9, 1921.

Application filed July 6, 1920. Serial No. 394,357.

To all whom it may concern:

Be it known that I, LEWIS M. KELLOGG, a citizen of the United States, residing at South Pasadena, in the county of Los Angeles and State of California, have invented 5 new and useful Improvements in Cascade-Amalgamators, of which the following is a specification.

My invention relates to improvements in 10 mercury amalgamators in which mercury is used to recover precious metals from their ores and sands, and the objects of my invention are to provide in such a device a means by which the mercury is broken into globules and disseminated through the ore pulp 15 followed by an adequate means for collecting and reuniting the mercury; more specifically to provide a terraced mercury cascade over which the mercury and ore pulp 20 are caused to flow in intimate association; the device consisting of the novel features herein shown described and claimed.

With reference to the drawings:

Figure 1 is a diametrical sectional elevation 25 of the device.

Fig. 2 is a fragmentary top view of the right hand side of the device as shown in Fig. 1, with an ore feed hopper removed.

Fig. 3 is a fragmentary top view of left 30 hand side of the device, as shown in Fig. 1 with a rotating cover removed.

In carrying out my invention a circular basin 1 is provided at the center of which is erected a cascade structure 2 comprising 35 the terraces 3, 4 and 5 each terrace being provided with an annular mercury basin 6, 6, 6. Through the center of the cascade structure is formed a bearing in which is rotatably mounted a shaft 7.

The floor of the basin is substantially flat 40 and is encircled by a low wall 8. From the rim of the wall and extending outwardly is a bib 9 having a mercury coated surface which is inclined toward the basin. Horizontally 45 through the wall is formed a mercury discharge port 10. A mercury discharge means 11 is positioned on the bib having a channel 12 in open communication with the mercury discharge port, a chamber 13 extending above the level of the bib 9, a filter element 13^a within the chamber, a mercury seal 14 and a rim 15, and being provided with a mercury discharge conduit 16 and a cleaning water conduit 17^a. The 50 discharge conduit 16 is connected to the 55 discharge side of a gear pump 17 by the opera-

tion of which the mercury is passed upwardly to the head of the cascade by the conduit 18. A tailings discharge launder 19 is disposed about the basin.

60

A rotating cover 20 is fixed to the top of the shaft 7 and overhangs the cascade 2, the basin 1 and the bib 9. That part which surrounds the cascade conforms to the terraces and is spaced therefrom forming an 65 annular channel 21; that part which covers the basin is disposed at such a level that it is partly submersed into a body of mercury, the normal level of which is shown by a dotted line 22 and that part which overhangs 70 the bib 9 rotates closely thereto providing a tailings discharge crevice 23.

An ore feed hopper 24 is mounted upon the top of the cover and above the cascade and which is in open communication with 75 the channel 21 of the cascade structure by means of ports 25.

Anode pockets 26 are disposed about the cascade cover having porous bottoms 27 and insulating linings 28, and within the pockets 80 thus formed are placed replaceable anode elements 29. A conductor ring 30 is fixed to the top of the cover and insulated therefrom.

A brush 31 fixed to the chamber 13 and 85 insulated therefrom is provided to carry current to the ring 30 from which it passes to the anodes 29 by conductors 32.

In the operation of the device, mercury is filled into the basin 1 up to the level of the 90 dotted line 20 and into the basins 6, 6, 6 of the cascade, the outside mercury system being also filled.

The mercury entering at the head of the cascade from the pump 17 overflows each 95 succeeding terrace 3, 4 and 5 falling into the basins 6, 6, 6, thence into the main basin 1 from which it overflows through the port 10, through a filtering element 13^a, under the seal 14, over the rim 15 and again to 100 the pump 17 by the conduit 16.

The shaft 7 is rotated slowly by any suitable means, such as the worm gear shown in Fig. 1, thus rotating the cover 20. Ore pulp carried in an adequate flow of water is 105 entered into the hopper 24 from which it passes down into the channel 21 by the ports 25. Here it meets and mingles with the mercury flow breaking the latter up into globules, and the mercury and pulp then 110 pass down and over the terraces to the main basin 1 in a spiral course due to the rota-

tion of the cover. In the main basin the mercury separates from the pulp forming a lower stratum with the ore pulp riding on top of the mercury and between it and the 5 undersurface of the rotating cover. At the rim of the basin the mercury overflows through the port 10, the mercury not being allowed to touch the top of the port and the ore pulp being restrained from passing out 10 of the basin over the surface of the discharging mercury by a counter current of cleaning water entered into the chamber 13 by the conduit 17^a. The scum which forms on the mercury body in the process of amalgamation passes out on the surface of the 15 mercury and is caught in the filter element 18^a. The ore pulp riding on the surface of the mercury passes out over the mercury coated bib 9 and away by the channel 23. 20 The electric current flow passes from the anodes through the porous bottoms through the pulp and globules of mercury and into the cascade structure or into the mercury held in the basins 6, 6, 6 returning to its 25 source by a return conduit 33.

Thus amalgamation is carried on in the mercury cascade where globules of mercury are intimately mixed with the ore or pulp and in the main basin where the pulp is 30 moving under pressure between the surface of the mercury and the rotating cover, the bib acting as an amalgamator of particles of mercury which may become detached from the body in the basin, the bib surface 35 being inclined toward the basin in order that the mercury which is caught may drain back thereinto.

The cascade structure may have any number and any width of terraces, and it is to 40 be understood that the exact form of the cascade structure and of its overhanging cover forms no part of my present invention, and that other changes may be made in the detail of construction and the arrangement of parts without departing from the 45 spirit of the invention as claimed.

Having thus described my invention, I claim:

1. In a mercury amalgamator in combination, a cascade comprising a series of annular terraces, a shallow mercury basin extending 50 outwardly from the base of the cascade and having an annular retaining wall, a mercury discharge port formed through the wall of 55 the basin and extending above and below the normal mercury level, a rotatably mounted cover for the cascade and the basin adapted to rotate closely thereto and thereover, means for feeding mercury to the head of the cascade and means for passing ore pulp over 60 the cascade with the overflowing mercury.

2. In combination in a mercury amalgamator, a mercury cascade comprising a plurality of annular terraces, a rotatably mount-

ed retaining cover conforming to the contour of the terraces and properly spaced therefrom, means for carrying mercury to the head of the cascade, means for collecting and reuniting the mercury at the base of the cascade and means for passing ore pulp over the cascade with the flow of mercury.

3. In a mercury amalgamator in combination, a mercury cascade, comprising a plurality of annular terraces, a mercury basin 75 formed in the top of each terrace, a rotatably mounted retaining cover conforming to the contour of the terraces and properly spaced therefrom, means for admitting mercury to the head of the cascade, means for 80 collecting and reuniting the mercury at the base of the cascade, and means for passing ore pulp over the cascade with the cascading mercury.

4. In combination in a mercury amalgamator, an annular mercury cascade, a retaining cover for the cascade rotatably mounted and conforming to the cascade structure and properly spaced therefrom, anode pockets 85 formed in the cover adapted to carry electric anodes whereby a current may be passed from them through a descending flow of pulp and mercury, means for delivering mercury to the head of the cascade, means for collecting and reuniting the mercury at the base of 90 the cascade and means for passing ore pulp over the cascade in association with the cascading mercury.

5. In a mercury amalgamator, in combination, a circular mercury cascade comprising 100 a series of terraces, means for feeding mercury to the head of the cascade, a circular basin at the base of the cascade adapted to collect and reunite the mercury, means for 105 passing ore pulp over the cascade with the cascading mercury, an annular cover rotatably mounted over the cascade and over the basin its inner and under surface conforming to the cascade structure and the basin and properly spaced therefrom forming 110 a channel through which the pulp will flow in intimate association with the mercury in its passage over the cascade and as a floating stratum in passing through the basin.

6. A cover for a mercury cascade adapted to be rotatably mounted having an inner surface conforming to the cascade structure and adapted to be spaced therefrom whereby a substantially parallel channel will be 115 formed between it and the cascade surfaces, anode pockets formed in the wall of the cover having porous bottoms and linings of insulating material adapted to carry replaceable anode elements.

In testimony whereof I have signed my name to this specification.

LEWIS M. KELLOGG.
